UNITED STATES PATENT OFFICE.

JOHN P. DOELFEL, OF NEW YORK, N. Y.

MASHING APPARATUS.

SPECIFICATION forming part of Letters Patent No. 366,573, dated July 12, 1887.

Application filed January 27, 1887. Serial No. 235,694. (No model.)

To all whom it may concern:

Be it known that I, JOHN P. DOELFEL, a citizen of the United States, residing at New York, in the county and State of New York, have invented new and useful Improvements in Mashing Apparatus, of which the following is a specification.

This invention relates to improvements in mashing apparatus, as set forth in the following specification and claims, and illustrated in the accompanying drawings, in which—

Figure 1 is a front elevation, partly in section, of a mashing apparatus. Fig. 2 is a section in the plane αx , Fig. 1. Fig. 3 shows a modified form of stirrer.

Similar letters indicate corresponding parts. The letter A indicates a mash-tub.

B is a bearing for a main shaft, C. The main shaft C can be revolved by a bevel gear-wheel, D, keyed or firmly connected to the shaft C. A bevel gear-wheel, E, connected to a shaft, F, and pulley G, is shown as being adapted to impart motion to the bevel gear-wheel D. The revolution of the shaft C is communicated to arms H, keyed or firmly connected to the shaft C.

To the arms H are secured hangers I. As indicated in dotted lines in Fig. 1, the number of hangers I can be increased, if it is desired to give additional strength to the device. The hangers I support stirrer-shafts J, which stirrer-shafts are free to revolve about their own axes. As seen in Fig. 1, part of the stirrer-shafts J may also be supported by the main shaft C. The revolution of the stirrer-shafts J is communicated to stirrers K, firmly secured to the stirrer-shafts. The stirrers K may be made of any suitable shape—such, for example, as shown in Fig. 1, or as shown, for example, in Fig. 3. For heavy kind of work, the stirrer shown in Fig. 3 will be preferable.

The stirrer-shafts J are provided with cranks L, connected by links M P and pitmen N to gear-wheels Q. Suitable guides, O, in the arms H are provided for the pitmen N.

The gear-wheels Q receive motion from a bevel gear-wheel, S, by means of a gear-ring, T, secured to the bevel-wheel S and engaging the gear-wheels Q. The bevel-wheel S is free to turn independently of the main shaft C.

Motion is communicated to the bevel-wheel S by suitable means, such as a bevel gear-wheel, U, connected to a shaft, V, and pulley W.

The driving-shafts F V can be connected, if desired, by suitable gears, X Y, feathered on the shafts F V, so that said gears turn with the shafts F V; but said gears are free to move longitudinally along the shafts. When out of gear with one another, the shafts F V can be actuated independently of one another. As the bevel gear-wheel S is mounted loosely on the main shaft C, the stirrer-arms J, with the stirrers K, can be actuated while the main shaft C and the hangers H remain stationary.

The axles e of the gears Q are shown as being supported by a bearing or collar, d, mounted on the main shaft C. One end of the main shaft C is shown as being supported or steadied by a bearing, Z. The bearing Z, as also the hangers or arms a, supporting the driving-shafts F V, can be secured in any suitable way—as, for example, to a support, b—which may be the upper part of a room or the roof of a building.

The tub A may be provided with a roof, g. By having suitable openings, e, in the roof g the main shaft C and the driving mechanism for the stirrer shafts J can gain access to the interior of the tub A.

It will be noticed that by the construction shown in the drawings all the gears or toothed wheels and the driving-shafts F V are placed outside of the tub A. Said gears are thus not liable to become clogged or choked by the contents of the tub, and said gears are free to work easily, and the interior of the tub is easily cleaned. By having the stirrers K adapted to operate independently of the rotation of the main shaft C different velocities can be imparted to the stirrers and to the main shaft, which is at times an advantage to the operator. By having the gears X Y of different diameters different velocities will be imparted to the shafts F V when said shafts are connected by the gears X Y, and the different velocities of the driving-shafts F V can be made to impart different velocities to the main shaft C and to the stirrers K.

The gears X Y can be readily moved in a longitudinal direction along the shafts F V by

the hand of the attendant. As the gears X Y are feathered on the shafts F V, the attendant, by pressing laterally on the gears X Y, or by giving the gears X Y lateral blows with a suitable instrument—such as a hammer—will move the gears X Y into or out of engagement with one another, as may be desired.

By having all the gears located outside of the tub A the gears are not liable to become choked by the contents of the tub. It is also an advantage to have separate actuating devices for the shaft C and for the stirrers K, as thereby the respective motions of the shaft and stirrers can be regulated as desired. For example, the stirrers K, with their axis J, may be caused to revolve very rapidly while the shaft C is caused to turn with comparative slowness. The result is that the contents of the tub are thoroughly agitated as the stirrers K travel about the interior of the tub.

Heretofore a mashing-tun has been used wherein vertical stirrers are used in combination with centrifugal horizontal stirrers intermediate of the vertical stirrers. A churn has also been known in which a dasher or stirrer revolving in a vertical plane has been driven by pitmen from a crank-shaft, the cranks being so arranged that they pass the dead-points successively. I make no claim to any such devices.

What I claim as new, and desire to secure by Letters Patent, is—

1. The combination, with a tub, A, main shaft C, and stirrers K, connected to the main shaft, of driving-shafts F V, adapted to operate independently of one another, one of said driving-shafts being connected to the main shaft C, and the other driving-shaft being connected to the stirrers K, substantially as set forth.

2. The combination, with a tub, A, rotary main shaft C, and stirrers K, mounted on shafts

which are journaled in the main shaft and in supports carried by said shaft, of a driving-gear, S, loosely mounted on the main shaft, a gear-ring, T, on the driving-gear S, and gear-wheels Q, connected to the stirrer-shafts by pitmen and meshing with gear-ring T, substantially as set forth.

3. The combination, with a tub, A, rotary main shaft C, arms H, and stirrers K, mounted on shafts which are journaled in the main shaft and in supports carried by said shaft, of driving-gears S U, gear-ring T, gear-wheels Q, and connecting-rods or pitmen N, connecting the gear-wheels Q and stirrers K, said pitmen N having guides O, supported by the main shaft C, substantially as set forth.

4. The combination, with a tub, A, main shaft C, and stirrers K, mounted on shafts which are journaled in the main shaft and in supports carried by said shaft, of driving-shafts F V, having miter-gears meshing with gears on the main shaft C and connected by pitmen to the stirrer-shaft, and longitudinally movable gears X Y, for connecting said driving-shafts, substantially as set forth.

5. The combination, with a tub, A, main shaft C, and stirrers K, mounted on shafts which are journaled in the main shaft and in supports carried by said shaft, of driving-shafts F V, having gears meshing with gears on the main shaft C and connected with the stirrer-shafts by pitmen, said driving-shafts F V being located outside of the tub, substantially as set forth.

In testimony whereof I have hereunto set my hand and seal in the presence of two subscribing witnesses.

J. P. DOELFEL. [L.S.]
